UNITED STATES PATENT OFFICE.

REINHOLD H. WAPPLER, OF NEW YORK, N. Y.

ELECTRIC MACHINE.

1,218,022.

Specification of Letters Patent.

Patented Mar. 6, 1917.

Application filed January 4, 1916. Serial No. 70,103.

To all whom it may concern:

Be it known that I, REINHOLD H. WAPPLER, a citizen of the United States, residing in the city of New York, borough of Manhattan, in the county and State of New York, have invented new and useful Improvements in Electric Machines, of which the following is a full, clear, and exact description.

10 My invention relates to electric machines of a kind suitable for developing electrical currents and impulses of high potential and high frequency, and particularly to such machines adapted for therapeutical purposes 15 and using a spark or static discharge of unitary direction.

More specifically stated, I seek to improve mechanism of the type just mentioned by grouping together in a single machine of 20 simple and compact form various devices and parts heretofore employed separately, and merely correlated for purposes of convenience.

My invention further contemplates the 25 provision of means for causing air to circulate through and around the contact brushes employed in rectifying the electric discharges, and for forcing a circulation of air adjacent various other parts likely to be 30 come heated.

My invention likewise comprehends placing a transformer in close proximity to a rectifying disk used in connection therewith, the position of the transformer relatively to 35 the rectifying disk being such as to dispense with all necessity for using loose cables to connect these parts, and to promote accessibility thereof while maintaining a maximum of efficiency therein.

40 My invention also includes various forms and arrangements of parts, and combinations thereof, for improving the general efficiency of the mechanism.

Reference is to be made to the accompanying 45 drawings forming a part of the specification, and in which like letters indicate like parts.

Figure 1 is a perspective of my improved electric machine.

50 Fig. 2 is a top view of the same, partly in plan and partly broken away.

Fig. 3 is a section on the line 3—3 of Fig. 2, looking in the direction of the arrows.

55 Fig. 4 is a detail view, showing in section one of the wings carried by the rectifying disk and used for circulation of air.

Fig. 5 is a diagram of the wiring.

Resting upon a floor 6 is a metallic base 7 provided with a web portion 8 and with an opening 9. The web portion 8 is further 60 provided with a raised bead 10 integral therewith. A pedestal 11, secured upon the base 7, supports a triphase motor provided with a terminal plate 13 and three binding posts 14, 15, 16. Connected to these binding 65 posts are wires 17, 18, 19, through which currents are supplied for energizing the motor.

The motor is provided with a revolvable armature shaft 20, carrying a rectifying disk 21 which is of insulating material such as 70 micanite. The rectifying disk is disposed in a vertical plane crossing the general direction of the length of the base, and carries wings 22, in this instance two in number, held in position by fastenings 23 or otherwise secured as desired.

The rectifying disk also carries four contact sectors 24, 25, 26, 27, spaced equidistant, and a pair of connectors 28, 29. The connector 28 extends from the sector 24 to the 80 sector 25, the connector 29 similarly extending between the sectors 26, 27.

Disposed adjacent the path of travel of the contact sectors are four brushes 30, 31, 32, 33, spaced equidistant and adapted to be 85 engaged by the contact sectors 24, 25, 26, 27, as the rectifying disk is rotated.

I provide a number of standards, 34, 35, of insulating material, disposed in groups upon opposite sides of the base. The standards rest in sockets 38^a and are secured to the lugs 36, 37 by bolts 38. The lugs 36, 37 are integral with the base, and extend upwardly therefrom.

At 39, 40 are a pair of cylindrical electrodes, together serving as a prime conductor. These electrodes 39, 40 extend through the standards 34, 35 and are adjustable relatively to the same. For this purpose the standards are severally provided with slots 90 41 and with adjusting screws 42.

Telescopically engaging the electrodes 39, 40 are metallic extension bars 43, 44. A cross bar 45 of insulating material is supported at its ends by metallic posts 48, 50, carried 105 by these extension bars. Spark terminals 47, 49 are mounted respectively upon the slide 46 and the post 48, and between these spark terminals a spark 47^a may be formed, as indicated in Fig. 5. A conducting cord 46^a 110 connects the slide 46 with the extension bar 44, and a cord 46^b of insulating material, is

connected to the slide 46 for the purpose of shifting the same in order to vary the length of the spark.

5 A tank 51, made of insulating material and having the general form of a parallelopipedon, is supported by the base 7 and held firmly in position by aid of the raised bead 10 which circumscribes the lower end of the tank.

10 The brushes 30, 32 are supported upon insulators 52, 53, the latter extending horizontally from the tank 51. The brushes 31, 33 are carried by the electrodes 39, 40 and are in the same vertical plane as the brushes 30, 32.

15 Disposed upon opposite sides of the tank 51 are a pair of metallic posts 55, each provided with a foot 54 secured directly to the base 7. Each post 54 is of proper form to serve as a clamping plate, and adjacent each 20 of these posts is a clamping plate 56, connected therewith by bolts 56^a. Clamped between each post 55 and the adjacent clamping plate 56 is a field bar 57, made up of iron plates. In other words, the field bars 25 are laminated. Extending horizontally through the tank 51, from one of the field bars 57 to the other, are two cores 58, 59, also laminated. Primary windings 60, 61, are carried by the cores, and encircling the mid- 30 dle portions of these primary windings and cores are short sleeves 62, 63, of insulating material. These sleeves carry the secondary windings 64, 65 which are in series. The primary windings are in parallel with each 35 other, as indicated in Fig. 5, and are connected to leads 66, 67 whereby they are energized. The secondary windings 62, 63, are connected by wires 68, 69 with the brushes 30, 32.

40 There is a definite phase relation between the currents energizing the wires 66, 67 and those energizing the wires 17, 18, 19. That is to say, the rotation of the rectifying disk 21 should be so timed that when the voltage 45 of the secondary circuit is at its maximum the contact sectors 24, 25, 26, 27 should engage the brushes 30, 31, 32, 33, but the order in which a particular brush is engaged by the several sectors is constantly changing.

50 The tank is filled with plastic wax, which envelops the cores and windings of the transformer and is normally hard. As the windings begin to heat up, however, as they do in use, the wax becomes wholly or partially 55 melted and acts as an insulating oil commonly used in transformers.

The speed of the machine may be 1800 revolution per minute.

The operation of my device is as follows:—

60 The parts being assembled and arranged as shown and described, the electric power is turned on and the motor 12 is thrown into action, causing the rotation of the rectifying disk 21.

Since the primary windings are in parallel with each other with reference to the flow of the primary currents and since these currents are alternating, the brushes 30 and 32 are each of alternating polarity. First 70 the brush 30 is positive while the brush 32 is negative, and then the brush 30 is negative while the brush 32 is positive. I will suppose that, with the parts as shown in Fig. 5, the brush 30 is for the moment positive, 75 the brush 32 of course being for the same moment negative. A secondary or spark circuit may now be traced as follows:—Secondary windings 64, 65, wire 68, brush 30, sector 24, connector 28, sector 25, brush 31, 80 prime conductor including electrodes 39, 40, brush 33, connector 29, brush 32 and wire 69 back to secondary windings. This causes a spark to take place, in one direction, between the spark terminals 49, 47. The disk by its 85 rotation next brings the sector 31 into engagement with the brush 30 and the sector 27 into engagement with the brush 32. At the instant this is done, the polarity of the brushes 30, 32 is reversed so that a circuit 90 may be traced as follows:—Secondary windings, 64, 65, brush 32, sector 27 (now at bottom limit of its travel), connector 29, sector 26, brush 31, prime conductor (same direction as before), brush 33, sector 24, connector 95 28, sector 31, brush 30, and wire 68 back to secondary windings 64, 65.

Thus it will be noted that the secondary currents or discharges always take place in the same direction through the prime 100 conductor and spark gap, and the value of the machine, for purposes of therapeutics, is greatly enhanced.

The rotation of the rectifying disk 21 causes the wings 22 to move bodily around, 105 and in so doing to cause a circulation of air through and around each of the brushes. This prevents the brushes from becoming unduly heated, and so prolongs the life time of the brushes, as well as prevents excessive loss 110 due to the conversion of electric energy into heat.

I also find from experience that the forced circulation of air caused by the rotation of the wings 22 has a marked tendency to cool 115 the tank 51 and its contents. As the various windings become heated, the wax in the tank melts, and as it gradually becomes liquid it circulates by convection. The circulation of air caused by the wings 22 tends 120 to cool that part of the tank immediately adjacent the rectifying disk, and because of the circulation by convection of the liquid within the tank the contents of the tank are cooled to a considerable extent. Naturally, the parts which are cooled to the greatest extent are those in which the greatest heat would otherwise develop. The net result is that parts apparently remote from the air currents set up by the wings are 130

cooled effectively and the cooling effect is far reaching, especially when the machine is driven at a high speed, as is usually the case.

5 Again, the constant circulation of air cools the field bars 57, and as heat is conveyed to these bars by conduction from the cores 58, 59, the internal temperature of the tank is still further reduced.

10 It will be noted that the transformer as a whole has the general form of a flat body standing vertically and that it is disposed substantially parallel to the rectifying disk. This not only promotes compactness and 15 renders the parts readily accessible, but it also exposes the field bars 57 and various other parts in positions suitable for enabling them to be advantageously swept by the air currents.

20 I claim:—

1. In a device of the character described, the combination of a supporting frame provided with a base, a rectifying disk journaled upon said frame and having a general 25 plane which extends vertically, a tank mounted upon said base and extending vertically upward therefrom, said tank containing an insulating material, and a transformer of longitudinal form resting upon said base and extending upwardly therefrom so as to be substantially parallel with said rectifying disk, said transformer being disposed partially within said tank, and located at the proximate level of said rectifying 35 disk, and electrical connections extending from said transformer to said rectifying disk.

2. In a device of the character described, the combination of a supporting frame provided with a base, a rectifying disk journaled upon said frame and having a general plane extending vertically, a transformer supported by said base and extending vertically therefrom so as to be substantially parallel to said rectifying disk, said transformer being located at the proximate level of said rectifying disk, and electrical connections from said transformer to said rectifying disk.

3. In a device of the character described the combination with a rectifying disk carrying contact sectors and connectors extending from one of said contact sectors to another, of brushes for engaging said contact 55 sectors, a step-up transformer disposed adjacent said rectifying disk and having a secondary winding connected to said brushes, and wings carried by said disk for forcing a circulation of air adjacent said transformer, said brushes, said contact sectors and said connectors.

4. A device of the character described comprising a revolable rectifying disk, a step-up transformer disposed adjacent said rectifying disk and having a secondary 65 winding connected to said disk for the purpose of supplying thereto currents of high potential to be rectified, and mechanism controllable by movements of said disk for forcing a circulation of air against a portion of said transformer in order to prevent undue heating of said transformer while supplying said currents.

5. A device of the character described comprising a revolable rectifying disk, a 75 transformer located in proximity to said disk and electrically connected to said disk for the purpose of supplying thereto the currents to be rectified, a tank of insulating material in which a portion of said transformer is submerged so that another portion of said transformer is left exposed, said tank being disposed adjacent said disk, and mechanism controllable by movements of said rectifying disk for forcing a circulation of air against 80 said tank and against the exposed portion of said transformer.

6. In a device of the character described the combination of a base provided with sockets and upwardly extending lugs disposed adjacent said sockets, standards of insulating material fitted into said sockets and secured to said lugs, a prime conductor supported by said standards, a transformer mounted upon said base and insulated therefrom, a rectifying disk supported by said base and insulated from the same, and electrical connections from said rectifying disk to said transformer and to said prime conductor.

7. In a device of the character described the combination of a frame provided with a base, a tank mounted upon said base and containing a volume of insulating material, a transformer mounted upon said base and having a portion extending into said tank and into the insulating material therein contained, said transformer having the general form of a flat body extending vertically from said base, a rectifying wheel supported by said base and extending vertically in relation thereto, said rectifying wheel being parallel to said transformer and in close proximity to the same, electrical connections from said transformer to said rectifying wheel, and mechanism controllable by the rotation of said rectifying wheel for forcing a circulation of air adjacent portions of said transformer, said tank and said electrical connections.

REINHOLD H. WAPPLER.
